UNITED STATES PATENT OFFICE.

AVERY B. DODGE, OF NEW YORK, N. Y.

DESIGN FOR A KNITTED FABRIC.

SPECIFICATION forming part of Design No. 12,362, dated July 19, 1881.

Application filed June 13, 1881. Term of patent 7 years.

To all whom it may concern:

Be it known that I, AVERY B. DODGE, of the city, county, and State of New York, have originated and produced a new Design for 5 Knitted Fabrics, of which the following is a description, reference being had to the accompanying drawing, which represents a face view of a piece of knitting of my design.

This design is of necessity produced of two 10 colors, of which either may be considered as the ground and the other the pattern, as the ground and pattern are exactly alike—that is to say, consist of duplicate and alternating figures. Any two colors may be used. To 15 distinguish the pattern from the ground I have represented one as plain and the other as shaded with diagonal lines. To facilitate reference to the parts by letter, I will consider the part represented plain to be the pattern.

20 The pattern is composed of a series of rows

of curvilinear acute-angled V-shaped figures, a a, with interposed rows of curvilinear V-shaped figures c c in each row, having between them a series of inverted-V-shaped figures e e, which are broken or interrupted at intervals 25 by the said figures c c and the corresponding and alternating figures of the ground, the configuration of the ground corresponding exactly to that of the pattern.

What I claim as my invention, and desire to 30 secure by Letters Patent, is—

The design for knitted fabrics consisting of the V-shaped and inverted-V-shaped figures a a, c c, and e e, arranged as herein shown and described.

AVERY B. DODGE.
